TWO-MOTION SELECTIVE SWITCH

William Robert Rose, Coventry, England, assignor
to The General Electric Company, Limited,
London, England

Application September 9, 1948, Serial No. 48,421
In Great Britain September 22, 1947

12 Claims. (Cl. 179—27.52)

1

This invention relates to electro-magnetic step-by-step switches of the two motion type such as are used in telephone systems.

It is an object of our invention to provide a switch of the character described having improved structural features which enhance its efficiency, improve its accuracy of selection and facilitate its assembly.

In general, the improved structure constitutes a fixed shaft and a pair of concentrically disposed hollow cylindrical shafts mounted on the fixed shaft. One of the hollow shafts is arranged to be lifted by a vertical stepping magnet while it slides over the other hollow shaft. At the end of such vertical movement, the other hollow shaft is rotated on the fixed shaft by a rotary magnet, the other hollow shaft carrying with it the first hollow shaft to which switch wipers are fastened.

It is a more specific object of our invention to provide a shaft assembly in which free movement between the two hollow shafts other than that desired, is reduced to a minimum. This enables accurate positioning of the wipers on the contact banks to be effected.

Another specific object of our invention is a method of fixing the wipers to the shaft assembly, in such a manner that the wipers are accurately located thereon, are easily removable therefrom, and do not exert any distorting force.

Reference should now be made to the accompanying drawing in which Figure 1 is a sectionalised view of a switch shaft assembly according to our invention, Figure 2 is a view of part of the shaft showing the attachment of the wipers, Figure 3 another view of the shaft assembly showing the method of locating one of the hollow shafts relative to the other shaft, and Figure 4 is a wiper bracket assembly. It should be noted that the horizontal dimensions of Figure 1 have been increased relative to the vertical dimensions, in order to show the construction of the assembly more clearly.

In the figures it will be seen that the switch shaft assembly comprises a first fixed shaft 1 which is of solid construction. This shaft is located at its lower end by a hole in part of the switch framework 2 in which the shaft is a push fit. At its upper end, the shaft is provided with several conical depressions and a square shank 3, the shaft passing through another hole in another part of the framework 2 in which it is again an easy push fit. The depressions engage with a plunger 4 which is urged towards the shaft by a coil spring 5 compressed by a screw 6. Rotation of the shaft by the

2

shank 3 causes the plunger 4 to move in and out of the depressions on the shaft, which is held firmly every time the plunger engages with a depression. The purpose of this arrangement will be described later.

A second shaft 7 of the switch is reamed to be a smooth rotating fit on the shaft 1, and is located so that it may rotate but not slide thereon by the collar 8. This collar is fixed to the shaft 7 by screws (not shown), and the collar may also act as a cam to operate rotary off-normal or other springsets. The shaft 7 is provided with a rotary ratchet 9, which is driven when the switch is in use by a rotary magnet and pawl, the latter of which engages with the ratchet.

A third shaft is of composite character and consists primarily of a ratchet body 10 fastened as by soldering to a wiper carrier 11, the latter being in the form of a hollow cylinder provided on the outside with webs 12. The ratchet member 10 is located on the shaft 7 by means of a bearing 13 fixed to the member 10, and the latter is provided with the usual frustoconical teeth 14. These teeth extend sufficiently far around the shaft to enable it to be held in any position to which it is stepped by the vertical magnet, when the whole assembly is rotated. The vertical ratchet may engage with the teeth shown or alternatively and preferably the said teeth may be cut away opposite the point where the vertical pawl engages during vertical stepping, being replaced by a strip of teeth made of a harder material such as steel or aluminium-bronze, this construction reducing the wear on the teeth whilst enabling the member 10 to be made of softer material such as brass which is more easily machined.

By the means outlined it will be seen that a shaft assembly is provided in which the minimum possible shake of the various parts on each other has been ensured. It is also necessary that when the second and third shafts are rotated together under the influence of the rotary magnet, substantially no free rotary movement of the third shaft takes place relative to the second. To promote this action the second shaft member 7 is provided with a key 22. This key passes through the gap which is left in the member 10 which is cut away at 23. On the flat face left by this operation, two steel strips 24, 25 are mounted. The first strip 24 is fixed by screws in position in a jig so that its inner vertical face is exactly parallel with the axis of the assembly. The shaft 7 is now inserted through the bearing 13, and one edge of the key

put against the member 24. The strip 25, which is provided with elongated fixing holes, is brought against the other edge of the key and screwed in position so as to provide the minimum possible amount of free rotational movement of the shaft 7 relative to the outer shaft. Thus the latter may slide freely over the former, but not rotate relatively to it.

In view of the accuracy possible, and, in fact, necessary between the various shafts, it is advisable to ensure that the method of fixing the wipers to the cylinder 11 is such that substantially no distortion of the whole assembly is caused. We ensure this by providing the cylinder with webs 12 disposed 180° apart. These webs may be continuous or, as shown, portions may be cut away where desired. Each wiper assembly consists of a body member 26 having a curved inner surface of radius substantially equal to the outer radius of the cylinder 11. This body member is fitted at each end with a small plate 27 fixable to the body member by a screw 28. Each wiper may be made with a small cylinder shaft or other means for attaching the said wiper to the body. When a wiper assembly is to be fixed in position the screws 28 are slackened off and the wiper body placed on the shaft and slid in position, the body passing on one side of the webs and the fixing plates 27 on the other side. When the screws 28 are tightened the webs are gripped between the plates and the body, holding the whole assembly firmly in position without distortion of the cylinder 11, such as may be caused for example by its encirclement by a band which is tightened to hold wipers in position. Separate adjustment of the wiper tips relative to the contact bank is provided by means adopted to fix the wipers to the carrier.

To ensure return of the wipers to a normal position i. e. below and outside the contact bank, after the switch has been released from use, we provide two coil springs 17, 29, spring 17 is slightly compressed, when the assembly is in the said normal position, between the bearing 15 and the bush 16 but it is not fixed to either of these. The bearing 15 is fixed to the cylinder 11 and the bush 16 to the shaft 1 so that vertical movement of the cylinder and wipers compresses the spring 17. When the rotary magnet rotates the second shaft 1, the spring 29 is wound up. The lower end of this spring is fixed to the bush 16 and the upper end to the shaft 7; the spring is also given an initial turn or two by rotation of the shaft 1 by the shank 3, the plunger 4 preventing backward rotation of the shaft 1. Release in first a rotary and then a vertical direction is ensured by engagement of a guide (not shown) mounted on the framework and engaging with the frusto-conical teeth of the vertical ratchet.

It will be seen from the foregoing description that a wiper shaft assembly has been provided capable of relatively easy construction, having the minimum amount of unwanted relative movement between its parts, easy adjustment of the various tolerances, and minimum distortion by the various processes of assembly.

I claim:

1. A two-coordinate switch of the type used in telephone systems, said switch comprising a framework having two spaced elements, a first shaft with its ends in said elements and spanning the space therebetween, means to fixedly secure said first shaft to said framework, a second shaft, said second shaft being hollow and coaxial with said first shaft, said first shaft extending through

said second shaft and projecting beyond the ends thereof, means to mount said second shaft on said first shaft for rotational movement with respect thereto, said mounting means including means to prevent axial movement of said second shaft relative to said first shaft, a third shaft, said third shaft being hollow and coaxial with said first two shafts, said second shaft being partially disposed within said third shaft, means to mount said third shaft on said second shaft for axial movement with respect thereto, said last named mounting means including means to prevent rotation of said third shaft relative to said second shaft, and a wiper assembly attached to the third shaft.

2. A switch as set forth in claim 1 wherein the first shaft is fixed to one of the framework elements at one end thereof and is supported by the other framework element at the other end thereof, and wherein means is included to apply a rotary stepping force to the second shaft at a point near the framework element whereat an end of the first shaft is secured.

3. A switch as set forth in claim 1 wherein the second shaft is provided with a rotary ratchet of cylindrical form and the third shaft is provided with a vertical ratchet formed as a superimposed series of truncated cones.

4. A switch as set forth in claim 1 wherein the means to prevent rotation of the third shaft relative to the second shaft comprises a key on the second shaft and an adjustable slot on the third shaft, said adjustable slot being formed by a hardened steel strip carried by the third shaft with an edge thereof parallel to the axes of the shafts, a second hardened strip, and means to mount said second strip on the third shaft, said last named means permitting transverse adjustment of an edge of the second strip relative to the mentioned edge of the first strip, said edges of the strip being adjacent opposite longitudinal sides of the key.

5. A switch as set forth in claim 1 wherein the third shaft is provided with a pair of radially extending webs, each wiper assembly including a body having a pair of clamping means, one of which detachably engages one of the webs and the other of which detachably engages the other web, said body extending between said clamping means.

6. A switch as set forth in claim 1 wherein the third shaft is provided with a pair of radially extending webs disposed 180° apart about the axis of said shaft, each wiper assembly including a body having a pair of clamping means, one of which detachably engages one of the webs and the other of which detachably engages the other web, said body extending between said clamping means.

7. A switch as set forth in claim 1 wherein the third shaft has an inner diameter greater than the outer diameter of the second shaft, wherein the third shaft extends beyond the second shaft, and wherein the third shaft is provided with two bearings carried thereby, one of said bearings sliding on the second shaft and the other of said bearings sliding on the first shaft.

8. A switch as set forth in claim 1 wherein means is provided to restore the second and third shafts to a normal position, said means comprising two independent coil springs, one of said coil springs being under axial tension between one end of said third shaft and a fixed collar on the first shaft, and the other of said coil springs being under rotary tension, said

other coil spring being connected between the first shaft and the second shaft.

9. A switch as set forth in claim 1 wherein means is provided to restore the second and third shafts to a normal position, said means comprising two independent coil springs, one of said coil springs being under axial tension between the first and third shafts and the other of said coil springs being under rotary tension between the first and second shafts.

10. A switch as set forth in claim 1 wherein the third shaft is provided with a vertical ratchet formed as a superimposed series of truncated cones, and adapted to be engaged by a vertical stepping pawl when the ratchet is in a predetermined angular position with respect to the pawl, the portion of said ratchet engaged by the pawl during vertical stepping being made of a material harder than the remainder of the ratchet.

11. A switch as set forth in claim 1 wherein means is provided to restore the second shaft to a normal position, said means comprising a spring under rotary tension between the first and second shafts, the means to fixedly secure the first shaft to the framework including a spring-loaded plunger carried by the framework and disposed to engage a depression in the shaft so that an initial rotary restoring tension can be imparted to said spring by turning the first shaft.

12. A two co-ordinate switch of the type used in telephone systems comprising a framework, a first fixed shaft, a second hollow cylindrical shaft, a third hollow cylindrical shaft having a wiper contact assembly rigidly attached thereto, all of said shafts being coaxial, said first shaft

being secured to said framework at one of its extremities and supported by it at its other extremity, a collar and a first bush situated at the upper end of said second shaft and between said first shaft and said second shaft, said collar being situated partially within a circumferential groove in said first shaft, a rotary cylindrical ratchet integral with said second shaft, an adjustable width keyway between said second shaft and said third shaft comprising two adjustable hard metal strips on said third shaft between which is situated a spline formed on said second shaft, a vertical ratchet comprising a number of superimposed truncated cones integral with said third shaft, a fixed collar situated at approximately the mid-point of said first shaft and a second bush fixed to the lower end of said wiper contact assembly carrying hollow cylindrical shaft and axially slidable on said first shaft, an axially compressed spring situated around said first shaft and between said fixed collar at approximately the mid-point of said first shaft and said second bush, and a torsion spring firmly fixed to the upper part of said fixed collar and extending around said first shaft to the lowest portion of said second hollow cylindrical shaft, being firmly fixed thereto.
